UNITED STATES PATENT OFFICE

121,110

DESIGN FOR A COMBINED DESK AND ARTIFICIAL FIREPLACE

Robert Williams, New York, N. Y.

Application April 1, 1940, Serial No. 91,378

Term of patent 14 years

To all whom it may concern:

Be it known that I, Robert Williams, a citizen of the United States, residing at New York, in the county of Kings and State of New York, have invented a new, original, and ornamental Design for a combined Desk and Artificial Fireplace, of which the following is a specification, reference being had to the accompanying drawing, forming part thereof.

Fig. 1 is a front perspective view of a combined desk and artificial fireplace showing my new design with the desk in closed position.

Fig. 2 is a front perspective view thereof with the desk in open position.

It is to be noted that the other end of the article illustrated in the drawing is substantially like the end shown.

I claim:

The ornamental design for a combined desk and artificial fireplace, substantially as shown and described.

ROBERT WILLIAMS.
